HOLDER

Raymond T. Luck, Chicago, Ill., assignor to National Dairy Products Corporation, a corporation of Delaware

Application July 19, 1956, Serial No. 598,925

2 Claims. (Cl. 248—301)

This invention relates generally to holders. More particularly, this invention relates to holders featuring hooks for hanging recipe books and similar articles therefrom.

In retail marketing operations, inducements to the customers to buy various products frequently comprise the dispensing of so-called "give-aways." In marketing food products through grocery stores and the like, these "give-aways" may, for example, take the form of inclusions in the product box. However, in many cases the "give-aways" comprise items attached adjacent to or directly on the outer surface of the merchandise package, for customer viewing and access. One advantage of this latter marketing technique is that the particular "give-aways" associated with the sales product may easily be changed from selling area to selling area and from time to time to stimulate repeated sales of merchandise, and without substituting the products themselves.

Inclusions are frequently introduced into the box containing the product at the product manufacturing plant. Consequently, change in the type of "give-aways" would necessitate recalling and repackaging of the product, or replacement of the products with new samples containing the new "give-aways."

One standard method of attaching "give-aways" adjacent to or directly on the outer surface of the package containing the sales product, or the outer surface of the sales product itself, is carried out by means of an adhesive strip. However, certain disadvantages may be present in this method. For example, a certain loss of customer eye appeal may arise due to the appearance of the strip. Further, there may be difficulty in removing the adhesive strip from the surface of the package or product itself where substitution of the type of "give-aways" is desired. In addition, use of adhesive strips is time consuming and expensive. Furthermore, the strips may dry out and allow the attached item to drop off from the surface to which it is held before sale of the product. In addition, most adhesive strips are of the one-use type and cannot be reapplied to a surface, in the event that substitution of the attached item is desired.

Cost of the strips can be an important factor in marketing highly competitive products, such as breakfast foods, cake mixes and cheese products, particularly where there are relatively low margins of profit to the manufacturer per product item.

A new means of attaching "give-aways" or other classes of items for display has been discovered, comprising a low cost, durable, reusable holder, featuring a hook. The holder is especially adapted for use in commercial price mouldings and also may be easily attached to cardboard box or similar constructions containing sales products.

Accordingly, a primary object of the present invention is to provide a simple, low-cost, reusable holder, which holder is of attractive appearance.

A further object of this invention is to provide a durable holder having a hook.

Another object of this invention is to provide an article

2

holder especially adapted for use in retail marketing operations.

Other objects of this invention will be apparent from a study of the following detailed description, and accompanying drawings, of which:

Figure 1 is a perspective view of a holder in accordance with the present invention;

Figure 2 is a side view of the holder shown in Figure 1, the holder being in position in a price moulding;

Figure 3 is a perspective view of the holder shown in Figures 1 and 2 in position in a carton;

Figure 4 is a view, partly in section, taken along the section line 4—4 of Figure 3.

The holder of the present invention is attachable to shelving, dairy cases, produce cases, frozen food cases and other product container units having price mouldings or similar equipment. These mouldings usually comprise vertically spaced slots which receive celluloid or paper numbers indicating the prices of the adjacent consumer sales products. Figure 2 shows the holder of the present invention held in position on such a moulding. Figure 3 demonstrates a further use to which the holder of this invention may be put, that is, attachment to cardboard or other easily scorable display cases and similar packages containing the sales product.

Now considering in detail the embodiment shown in Figures 1, 2, 3 and 4, holder 5 comprises a relatively thin, resilient section 7. The holder also includes a hook 9, centrally disposed with respect to the section 7 and extending forwardly and upwardly therefrom.

The section 7 and hook 9, if desired, may be formed as a single unit from a suitable durable material such as metal, preferably aluminum or stainless steel, or a non-metal of requisite stiffness and resilience, such as plastic, natural or synthetic rubber.

One method of manufacturing the holder 5 is to stamp it out from a flat sheet of the material, preferably in a one-stamp operation which also cuts and shapes hook 9 from the body of the section 7. Other commercial methods of manufacture are also applicable for the fabrication of the holder 5. For example, the hook 9 may be formed as a separate unit and attached to the section 7. The holder 5 may have straight edges. Preferably the holder has edges at least some of which are rounded, as shown at 45

11.

As clearly shown in Figures 1 and 3, the illustrated hook is formed with a series of three successively and oppositely disposed curved portions. In addition, the hook is provided with a generally centrally disposed, longitudinal rib 9a which inherently rigidifies the hook.

This construction has the advantage of providing a more pleasing appearance and aids in the insertion of the holder into the tracks of a price moulding 13, as shown in Figure 2.

55 Edges 11 may be utilized for scoring a cardboard case 15 (see Figure 3) along the lines 17. In this regard, it is also contemplated that one or more edges of the holder may be formed if desired, to facilitate scoring of cardboard and the like.

60 The holder may be uncolored or may be suitably colored, as with paint, enamel or pigments incorporated in the body of the holder, if the holder is fabricated from a plastic, rubber, etc.

65 The holder 5 may be attached to any suitable pair of retaining means. As an example, the holder 5 may be attached to the price moulding 13 such as shown in Figure 2, which moulding may already be conveniently joined to a display counter 18. Accordingly, the entire holder assembly comprises section 7, hook 9 and the moulding 13.

70 The method of attachment of the holder 5, as provided in Figure 2, comprises merely bending the holder

5, to fit into the tracks 19 and 21 of the price moulding 13 with the hook 9 in the upwardly extending receiving position. Holder 5 may be, if it is flexible as preferred, slightly higher than the distance between tracks 19 and 21, so that when inserted between these tracks plate 7 of the holder is caused to "belly" or curve outwardly. This has the effect of automatically extending hook 9 outwardly and also tends to hold holder 5 more securely in place against the price moulding.

When it is desired to attach the holder directly to a cardboard case, containing the sales products such as case 15 in Figure 3, parallel lines 17 may be scored in the case a suitable distance apart by means of one or more edges 11 of plate 7, or by other suitable means as, for example, a knife or razor. The distance between the parallel lines may be slightly less than the total height of holder 5, if, as is preferred, holder 5 is flexible. After the lines 17 are scored in the case, holder 5 may be placed under slight compression so that edges 11 are bent toward each other. The total height of the holder is accordingly slightly reduced until it approximates the distance between score lines 17. Edges 11 of the holder may then be inserted into score lines 17 with hook 9 in the upwardly extending operative position. The compressive force is then removed from the holder. The resiliency of holder 5 will cause edges 11 to be driven further into the score lines 17, preferably between the layers 23 and 25 (Figure 4) of the cardboard case or other suitable container. The main portion of holder 5 accordingly is held in position adjoining the external surface of layer 23 of the cardbord case 15.

Holder 5 can be easily stripped from cardboard case 15 for reuse in another location whenever desired. When holder 5 is positioned as above described, the "give-away" items, for example, paper pads containing recipes imprinted thereon, or advertising data, etc. may be suspended from hook 9. The item to be suspended or hung from hook 9 may have holes punched therethrough for receiving hook 9. Such "give-away" items are shown by dotted lines in Figures 2 and 3.

Holder 5 may be manufactured in any size or shape to fit standard price mouldings or cardboard cartons, boxes, etc. A preferred embodiment of this invention is a stainless steel holder of the general shape of that set forth in Figures 1, 2, 3, and 4. The holder is approximately 1 1/4 inches high and 3/4 inch wide, a suitable size to fit a common type of price moulding found in most retail grocery stores. The holder has a hook which is approximately 1 3/16 inches in length and 3/16 inches in

width, and which is formed centrally of the plate in a stamping operation.

It is obvious that various modifications in the construction, shape, form and style of the present invention 6 can be made without departing from the spirit of this invention. All such modifications are contemplated as being within the scope of this invention.

I claim:

- 10 1. A holder comprising a thin, resiliently flexible, generally flat plate having formed integrally therewithin a generally centrally positioned, elongated hook located in an inoperative, generally co-planar relation relative to said plate, said hook having a longitudinally extending central rib making said hook relatively rigid with respect to said plate, said flexible plate being bendable to present a rearwardly concave disposition of the plate relative to said hook to thereby place the latter in forwardly spaced relation to said plate.
- 15 2. A holding assembly including, in combination, a holder and a pair of parallel tracks receiving said holder, said holder comprising a thin, resilient, generally rectangular plate having upper and lower edges disposed in generally parallel relation to each other and having formed integrally therewith a centrally located elongated hook disposed lengthwise in generally perpendicular relation to said upper and lower edges, said hook having a longitudinally extending central rib and being positioned in an inoperative, generally co-planar relation to said plate when said plate is flat, said upper edge of said plate being received by one of said tracks and said lower edge being received by the other of said tracks, said pair of tracks being spaced apart slightly less than the distance between said upper and lower edges of said plate, said plate being bowed for receipt by said tracks whereby said hook is automatically flexed forwardly of said plate from said inoperative, generally co-planar position relative to said plate to an operative position in adjacent spaced forward relation to said plate.
